UNITED STATES PATENT OFFICE

WILLIAM EMIL KESSLER, OF JERSEY CITY, NEW JERSEY.

PERISCOPE.

1,225,646.

Specification of Letters Patent.

Patented May 8, 1917.

Application filed September 30, 1916. Serial No. 123,181.

To all whom it may concern:

Be it known that I, WILLIAM E. KESSLER, a citizen of the United States, residing at Jersey City, in the county of Hudson and 5 State of New Jersey, have invented certain new and useful Improvements in Periscopes, of which the following is a specification.

This invention has relation to periscopes for submarine vessels or the like, and the 10 nature and objects thereof will be readily apparent to those skilled in the art to which it appertains in the light of the following explanation of the accompanying drawings illustrating what I now believe to be the 15 preferred embodiment, or mechanical expression, of my invention from among other forms and arrangements within the spirit thereof, or the scope of the appended claims.

However, an object of the invention is 20 to provide a periscope embodying an objective lens adapted for vertical movement within its support, said lens being movable to a position adjacent the lower end of the periscope so as to be accessible from within 25 the vessel whereby the lens may be cleansed, or replaced by a new lens when an objective has been broken through accident or design.

Another object of the invention is to 30 provide a periscope having the above named characteristics, and a new and novel means for producing vertical movement of the objective lens for the purpose above set forth.

In addition to the foregoing, my invention comprehends improvements in the 35 details of construction and arrangement of the correlated parts to be hereinafter more fully described, and particularly set forth in the appended claims.

In the accompanying drawings in which 40 similar and corresponding parts are designated by the same characters of reference throughout the several views in which they appear:

Figure 1, is a vertical sectional view taken 45 through a periscope constructed after the manner of my invention,

Fig. 2, is a similar sectional view taken on a plane at right angles to the plane of the foregoing view.

With reference to the drawings, 1 indicates the periscope tube secured at its lower end as at 2 to the roof plate 3 of a submarine vessel, and provided at its upper end with a lateral opening 4, to the rear of 50 which the objective lens is normally seated. Opposed mirrors 5 are located at the upper

and lower ends of the periscope in parallelism, the upper ones being designed to receive the rays from the objective lens and to direct said rays downward toward the 60 second mirror through an intermediate lens 6, an eye piece 7 being located at the lower end of the periscope through which to view the reflection in the lower mirror. Thus far, the construction is that of a conventional 65 form of periscope.

For the purposes of the present invention, the objective lens 8 located normally at the upper end of the periscope is mounted in a casing 9 or block, formed with a vertical 70 groove 10 at either side, for the purpose of receiving the edges of vertical guide strips 11 extending from top to bottom of the periscope within the tube 1, and secured at their upper ends as indicated at 75 12 by suitable fastenings, and at their lower ends as indicated at 13 to framing within the submarine vessel. The strips 11 are disposed at opposite sides of the periscope tube and therewithin, to guide the casing 9 containing the objective lens for vertical movement, and it will be obvious that owing to this arrangement the objective lens is capable of movement from an uppermost position within the opening 4, to an extreme 80 lowermost position, permitting access to the lens from within the submarine vessel.

One of the guide strips 11 is spaced from the inner side of the periscope 2, and a vertically extending threaded shaft 14 is interposed therebetween journaled in bearings 15 at its upper end, and 16 at its lower end, thereby permitting rotation of said shaft. The casing 9 of the objective lens is provided at one side adjacent the threaded shaft 95 with an extension 17, provided with a vertically extending internally threaded opening designed to receive in threaded engagement the shaft 14. A casting 18 is secured to the inner side of the roof of the submarine vessel for the purpose of forming a support for the bearing 16, and for a transversely extending shaft 19. A gear wheel 20 is mounted upon the shaft 19 and is formed with inclined teeth designed for meshing 100 engagement with the threaded portion 21 at the lower end of the threaded shaft 14, the gear wheel 20 being provided with a handle permitting manipulation thereof.

It will be obvious, that upon rotation of 110 the gear wheel 20, its movement is communicated to the threaded shaft 14, and

owing to its present engagement with the objective lens casing 9, said lens casing and consequently the lens inclosed therein is moved within the periscope tube in a vertical direction, either up or down, depending upon the direction of rotation of gear wheel 20. The objective lens and its casing are normally disposed at the upper end of the guide strip 11 thereby disposing the lens to 10 the rear of the opening 4. When, however, the lens is pierced through accident or by design, or the lens is purposely blurred by the enemy when the craft is used in an engagement by casting oil upon the surface of the 15 water, the lens and its casing may be quickly moved to the lower end of the periscope, so as to permit cleaning of the lens, or replacement thereof by an unbroken lens, whereupon the lens in the objective may be 20 then quickly moved to the upper end of the periscope tube in place.

While I have illustrated and described my invention with some degree of particularity I realize that in practice various alterations thereover may be made, and I therefore reserve the right and privilege of changing the form of the details of construction, or otherwise altering the arrangement of the correlated parts without departing from the spirit of the invention or the scope of the appended claims.

Having thus described my invention what I claim as new and desire to secure by Letters Patent is:—

- 35 1. In a periscope, a tube, an objective lens movable longitudinally within the periscope tube from its normal position to a position permitting access thereto for cleaning or repair, and means for causing such movement.
- 40 2. In a periscope, a tube, an objective lens movable longitudinally within the periscope tube from its normal position to a position permitting access thereto for cleaning or repair, and means for causing said movement,

Copies of this patent may be obtained for five cents each, by addressing the "Commissioner of Patents, Washington, D. C."

said means automatically retaining said lens 45 in its adjusted position.

3. In a periscope, a tube, an objective lens therewithin, means for moving the lens longitudinally within the periscope tube from its normal position therewithin to a position permitting access to the lens for cleaning or repair and means for guiding the lens 50 during such movement.

4. In a periscope, a tube, an objective lens adapted for movement longitudinally within the periscope tube, means for guiding the lens in such movement, and means for moving the lens along its guide, said moving means acting automatically to retain the 55 said lens in adjusted position.

5. In a periscope, guide-ways extending longitudinally within the tube, an objective lens, a casing for said lens mounted for movement between the guides, and means for moving said lens casing and lens from 60 its normal position, to a position permitting access thereto for cleaning or repair.

6. In a periscope, a tube, guide-ways extending longitudinally within the periscope tube, a casing movable between the guides, 70 an objective lens mounted within the casing, a lateral extension on said casing having a threaded aperture, a threaded shaft extending longitudinally within the periscope tube and within the threaded opening, and gearing for rotating said shaft thereby causing longitudinal movement of the casing and lens within its guide from the normal position of the lens and casing to a position permitting access thereto for cleaning or repair. 75

In testimony whereof I affix my signature in presence of two witnesses.

WILLIAM EMIL KESSLER.
